(57) **CLAIM**

The ornamental design for a USB memory device, as shown and described.

DESCRIPTION

FIG. 1 is a top view of the USB memory device, the bottom being a mirror image thereof.

FIG. 2 is a front view of the USB memory device.

FIG. 3 is a right side view of the USB memory device, the left side being a mirror image thereof.

FIG. 4 is a rear view of the USB memory device.

FIG. 5 is a top, front, right perspective of the USB memory device; and,

FIG. 6 is a top, front, right perspective of the USB memory device with the USB connector in an extended position.
